UNITED STATES PATENT OFFICE.

REINHOLD SCHNEIDER, OF SHARON, PENNSYLVANIA.

HYDROCARBON-BURNER.

1,192,573.

Specification of Letters Patent. Patented July 25, 1916.

Application filed December 13, 1912. Serial No. 736,573.

To all whom it may concern:

Be it known that I, REINHOLD SCHNEIDER, a citizen of the United States, and resident of Sharon, in the county of Mercer and 5 State of Pennsylvania, have invented a new and useful Hydrocarbon-Burner, of which the following is a specification.

My invention relates to the construction of hydrocarbon burners, and more particularly relates to burners for tar and similar liquid fuels constructed and arranged for use in connection with metallurgical furnaces.

One object of the invention is to provide 15 a liquid fuel burner adapted for use in burning tar and similar hydrocarbons having novel means whereby coking of the tar on the interior of the apparatus is avoided and overcome.

Another object of my invention is to provide 20 a liquid fuel burner having novel means whereby the discharge end or nose of the burner is effectively prevented from becoming overheated and is protected against burning.

A further object of this invention is to 25 provide a liquid fuel burner having novel means whereby the burner is cooled and by which cooling of the liquid fuel in the burner is prevented.

A still further object of the invention is to 30 provide a burner having novel means whereby the quantity of fuel passing through the apparatus is regulated and controlled and 35 by which the fuel conduit is cleaned and clogging of the fuel conduit is prevented, without necessarily removing the apparatus from the furnace.

A still further object of this invention is 40 to provide novel means whereby the burner is movably secured in operative position, and is adjusted and held in lengthwise and angularly adjusted position.

Still further objects of my invention will 45 be disclosed hereinafter as the invention is more fully described and claimed.

Referring to the drawings, forming part 50 of this invention, Figure 1 is a sectional side elevation of a regenerative open hearth furnace showing a hydrocarbon or liquid fuel burner constructed and arranged and applied for use thereon in accordance with 55 my invention. Fig. 2 is a longitudinal section, on a larger scale, showing in detail one form of hydrocarbon burner as constructed and arranged in accordance with

this invention. Fig. 3 is a sectional end elevation of the burner shown in Fig. 2, the section being taken on the line III—III of Fig. 2. Fig. 4 is a sectional end elevation of the same on the line IV—IV of Fig. 2.

In the accompanying drawings, the numeral 2 designates a pipe forming a conduit for the tar or other liquid fuel, terminating at the discharge end of the burner in a nose having an outwardly tapering nozzle 3 which is adapted to be engaged by the tapering end 4 of the rod forming the needle valve 5 by which the size of the opening in 70 the burner end of the conduit 2 is varied in regulating the supply of liquid fuel passing through the burner into the furnace or other point of use.

The conduit 2 has a series of projections 75 6 which are spaced at intervals on the inner surface of the conduit 2 adjacent to the nose end thereof to center and maintain the longitudinally movable rod forming the needle valve 5 in axially central position 80 therein.

The rear end of the pipe or fuel conduit 2 extends through registering openings in opposite sides of the hollow casting forming 85 the casing 7, the rear end of the pipe 2 being screw threaded into one end of the valve body 8. The valve body 8 is screw threaded by one end into the internally threaded opening 9 in one side of the casing 7, and a side outlet 10 is provided on the valve body, 90 having a hose connection 11 thereon, which is connected by its other end to a source of liquid fuel supply.

The rear end of the rod forming the needle valve 5 is provided with a screw threaded portion 12 which extends through the internally threaded portion 13 of the valve body 8, and the enlarged end of the valve rod 5 beyond the screw threaded portion 12 thereof extends through a stuffing box 14 and gland 15 on the valve body and is provided with a handwheel 16 on the end thereof by which the valve rod 5 is moved to adjust the tapering end 4 of the valve rod 5 within the nozzle 3 on the nose end of the conduit 2 and, when necessary, to shut off the supply of tar or other fuel. The pipe 2 forming the liquid fuel conduit is telescoped within the larger hollow passage 17, one end of the tube forming this surrounding passage 17 being screw threaded into the internally threaded opening 18 in one side

of the casing 7. The tube 17 has an integrally formed outer wall 19 of larger diameter which in turn surrounds the wall of the tube 17 for a portion of the length of this tube so as to form a hollow water jacket for the air conduit 17. A ring 43 is welded or brazed on the tube 17, this ring being seated on the header 21 by screwing the outer wall or shell into the header 21. The rear end of the shell or wall 19 is screw threaded into the opening 20 in the front end of the header 21 and the header 21 also has a partition therein which has an internally threaded opening 22 into which one end of the pipe 23 is screw threaded.

The pipe 23 projects forwardly between the inner and outer walls of the jacket 19 so as to form a diaphragm or partition separating the jacket 19 into two concentric water spaces for a purpose described hereinafter. Screw threaded into the rear end of the header 21 is the male member 24 of a union 25 by which the water supply pipe 26 is secured to the jacket 19 so as to be readily detachable. A similarly formed union 27 has a male member 28 screw threaded into an opening in the header 21 to detachably connect the water overflow pipe 29 to the jacket. The casing 7 is provided with a screw threaded inlet 30 to which a flexible tube or other connection 31 is secured, through which air is supplied under pressure to the air passage in the burner.

The nozzle end of the tube 2 terminates at the forward or nose end of the burner so as to form an annular air outlet 2^a between the outer wall of the tube 2 and the inner wall of the pipe 17. The inner surface of the pipe 17 is provided with a series of projections 32 near the outlet end of the air passage to center the outer end of the pipe 2 within the pipe 17 and form an annular discharge opening at the outlet end of the burner surrounding the discharge outlet opening in the pipe 2 forming the fuel conduit. Lugs 33 are conveniently formed on the casing 7 to provide means at the rear end of the burner for suspending and maintaining the burner in position in the ports of the furnace.

When the burner is used on an open hearth or similar metallurgical furnace, the furnace 34 is provided with one or more suitable port openings 35 in the ends of the furnace and the burners are suspended from a trolley 36 with their discharge ends projecting into the port openings. The trolley is mounted upon the track 37 formed by the bent bar which is conveniently secured to the buckstays or metal framework 38 at the ends of such furnaces. The trolley 36 is provided with anti-friction rollers or track wheels 39 arranged to engage with the track 37 and hold the burner in operative position and to permit the burner while so held to be

moved lengthwise, to advance the nose of the burner for the desired distance into the port opening 35 and to retract the burner as required. The burner is secured at one end by the lugs 33 thereon to an eyebolt 40 by means of which the burner is suspended from the trolley 36 on the track 37.

It will be obvious that the arrangement of the rollers or wheels 39 on the trolley 36 so as to engage opposite sides of the track 37 will prevent any tendency of the overhanging nose of the burner to tilt the trolley in moving the trolley on the track 37.

As it is sometimes found to be desirable or necessary to adjust the burner angularly within the port opening 35 so as to point the burner lengthwise at the desired angle to the horizontal, an eccentric or cam 41 is provided on the lower end of the trolley 36 which engages with a rib or flange on the rear end of the burner and is provided with a handle 42 by which the cam is turned to cause the nose of the burner to move from the position shown in full lines into that shown by dotted lines in Fig. 1 or, into an intermediate position as required.

When desired, the burner is moved lengthwise by shifting the trolley 36 on the trolley track 37 so as to move the burner backwardly from the position shown until the nose thereof is entirely without the furnace end walls where it can be readily inspected, and the distance the burner is caused to project into the port opening 35 can, in the same manner, be varied as is found desirable.

It will, of course, be understood that two or any desired number of burners can be applied for use on each end of the furnace, as is found necessary, a suitable number of port openings 35 being provided in such case in the ends of the furnace.

In the operation of my improved burner, when applied for use on a furnace, such as that shown, the parts are assembled as shown, the pipe or tube 11 is connected with a source of tar or other liquid fuel supply. The inlet opening 30 on the casing 7 is connected by the pipe 31 with a source of air or other fluid under pressure such as dry steam, and the water inlet pipe 26 is connected with a source of water supply, and the outlet pipe 29 to an overflow outlet opening.

In some cases the water supply pipes 26 and 29 will be connected to a water tank or trough in such manner as will cause the water used in cooling the nose of the burner to circulate from the tank through the burner and back to the tank again, in this way the same volume of water being used over and over for an indefinite period.

The valve, which will be provided in a suitable location on the pipe 31 leading to the air inlet 30, being opened, air under

pressure is caused to pass into the casing 7 and through the conduit 17, passing out through the annular opening 2⁵ in the nose or outlet end of the burner. The inlet valve which will be provided on the pipe 11 then being opened, the tar or other liquid fuel being used, being under pressure of a sufficient head, is caused to flow through the pipe 11 and valve body 8 into the conduit 2, 10 finally passing through the central fuel opening 3 in the nose or outlet end of the burner. In the meantime, water is caused to circulate through the pipes 26 and 28 and through the shell or jacket 19 of the burner, 15 the diaphragm or partition 23 in the jacket 19 causing the water to pass from the pipe 26 to the front or nose end of the burner and then backwardly and out of the jacket through the outlet pipe 29. Obviously, the 20 connections can be reversed, and the water caused to enter through the pipe 29 and pass out of the jacket through the pipe 26.

After the flow of air is started and the tar begins to discharge from the nose of the 25 burner, the volume of tar passing through the annular tar outlet opening is regulated by turning the handwheel 16 and adjusting the needle valve rod 5 projecting through the outlet end of the fuel conduit 2. The 30 valve on the pipe 31 controlling the air supply is also turned to regulate the air supply and permit the necessary quantity of air being supplied.

The tar under pressure is forced through 35 the conduit 2 and as it emerges from the nose of the burner it is caused to intimately mix with the surrounding annular stream of air passing through the conduit 17 and is atomized and discharged into the furnace 40 where the mixture of tar and air is burned. The tar is not chilled by the water cooling effect of the water jacket 19, as the tar conduit 2 is insulated from the water cooling jacket 19 by the surrounding stratum or 45 layer of air passing through the conduit 17 telescoped over the conduit 2, while the circulation of water in the water jacket maintains the burner in the necessary cooled condition when used on metallurgical furnaces employing extreme temperatures.

The advantages of my invention will be apparent to those skilled in the art.

Modifications in the construction and arrangement of the parts may be made without departing from my invention as defined in the claims.

I claim:

1. A liquid fuel burner comprising in combination, a fuel conduit having a discharge outlet, an annular air passage surrounding the fuel conduit and having an

annular discharge outlet around the fuel discharge outlet, the fuel conduit and air passage having coacting means for centering the discharge end of the conduit within 65 the annular discharge outlet, the discharge end of said air passage having a double wall forming a hollow water jacket on the nose of the burner and a header secured to the rear end of the water jacket having water 70 supply and outlet openings therein, said air passage and fuel conduit extending rearwardly through the header and having air and fuel supply connections thereon.

2. A liquid fuel burner comprising in 75 combination, a fuel conduit having a discharge outlet, an annular air passage surrounding the conduit and having an annular discharge outlet around the fuel discharge outlet, the discharge end of said air 80 passage having a double wall forming a hollow water jacket surrounding the nose of the burner, means for supplying air to the air passage and water to the water jacket, a removable needle valve adjustably 85 mounted in said conduit and arranged to engage with the fuel discharge outlet for closing the fuel conduit, said needle valve being removably secured in said fuel conduit, and means on the inner wall of said 90 fuel conduit for centering the end of the needle valve within the conduit.

3. The combination with a furnace having a fuel inlet port, of a fluid fuel burner projecting into said port, a trolley, means 95 pivotally connecting said burner to the trolley, said means being arranged to adjust the burner vertically relative to the trolley, a trolley track secured to the furnace on which the trolley is mounted, said trolley being 100 movable on the track to shift the burner into and out of position within said port, and means on the trolley engaging the rear of the burner for adjusting the burner angularly within said port.

4. The combination with a furnace having a fuel inlet port, of a liquid fuel burner projecting into said port, a trolley from which said burner is suspended, a track secured to the furnace on which the trolley is 110 mounted, said trolley being movable on the track to shift the burner into and out of operative position in said port, and a cam on the trolley arranged to engage the rear end of the burner to adjust the burner nose 115 angularly relative to a horizontal plane.

In testimony whereof I have hereunto set my hand.

REINHOLD SCHNEIDER.
